BEVERAGE COOLER

Aaron Wiley Sherwood, Hackensack, N. J., assignor to Associated Engineering, Inc., Glen Rock, N. J., a corporation of New Jersey

Application September 26, 1938, Serial No. 231,635

18 Claims. (Cl. 62—141)

The invention relates to the cooling of brewed beverages, such as beer and ale, for storage and dispensing.

It is the custom of ship brewed beverages, such as draught beer and ale, from the brewery to the tavern, restaurant or other place of consumption in wooden or metal kegs and to store the beverage in and dispense it from these kegs or containers.

According to one form of the invention the beverage is cooled by withdrawing limited amounts from the keg, subjecting the withdrawn amounts to refrigeration and then returning them to the keg. If desired, the apparatus for performing this operation may be associated with the tapping apparatus for tapping the beverage for dispensing, and the compressed air system, normally used in maintaining dispensing pressure within the keg, may be utilized for withdrawing beverage from and returning it to the keg.

Such apparatus may comprise a concentric tap rod arrangement having an inner dispensing tube leading to the dispensing faucet and an outer transfer tube connected to a cooling chamber located above the keg. The cycle may be controlled by a rotary valve and a diaphragm device, which alternately reduce the pressure at the top of the cooling chamber, causing the beverage to pass through the transfer tube into the cooling chamber, and alternately apply keg pressure to the cooling chamber, causing the beverage to return to the keg through the same tube. Both tubes of the tap rod preferably extend close to the bottom of the keg so that the beverage may be completely dispensed and so that the beverage at the bottom of the keg may receive direct cooling action.

A further feature of the invention is the placing of the keg being dispensed in an insulated cabinet along with one or more storage kegs. The refrigeration applied to the keg being dispensed is applicable, not only to keep this beverage at dispensing temperature, but also to maintain the interior of the cabinet and the beverage in the storage kegs at proper storage temperature.

The invention also consists in certain new and original features of construction and combination of parts hereinafter set forth and claimed.

Although the novel features which are believed to be characteristic of this invention will be particularly pointed out in the claims appended hereto, the invention itself, as to its objects and advantages, and the manner in which

it may be carried out, may be better understood by referring to the following description taken in connection with the accompanying drawings forming a part thereof, in which

Fig. 1 illustrates somewhat diagrammatically a layout of the beverage cooling system according to the invention;

Fig. 2 is a vertical section through the tap rod, cooling chamber and beer keg;

Fig. 2a is a detail showing the position of the two-way valve during tapping;

Fig. 3 is a detail illustrating sections through the control valve and diaphragm meter;

Figs. 4, 4a and 4b are sections on the lines 15 4—4, 4a—4a and 4b—4b of Fig. 3;

Fig. 5 is a vertical section illustrating a preferred form of cooling chamber;

Fig. 6 is a bottom plan view of the top member of the cooling chamber shown in Fig. 5

In the following description and in the claims, various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings and, more particularly, to Fig. 1, the general layout of the system for carrying out the invention will first be described. The reference character 10 indicates the back edge of an ordinary dispensing bar or serving counter, such as used in taverns, bar rooms and restaurants. Back of the bar is shown an insulated keg chamber or cabinet indicated by 11. This cabinet 11, in the form shown, is made to accommodate two conventional beer kegs, indicated by 12 and 13. The keg 12 has the cooling system of the invention applied thereto. The keg 13 is stored within the cabinet 11 without any cooling or dispensing apparatus connected thereto.

The keg 12 has applied thereto a tap rod assembly 16. Surrounding the upper part of the tap rod 16 is a cooling chamber 15 to which the beer in the keg is periodically transferred for cooling and returned to the keg. A conventional dispensing faucet 14 is connected to the upper end of the tap rod 16.

A conventional refrigerating system, indicated

in general by 19, is connected to the cooling coil 33 of the cooling chamber 15 for cooling the beer to the desired temperature.

A conventional air compressor 20 and compressed air storage tank 21 may also be provided for maintaining the proper pressure within the keg 12 and for operating the beer cooling system. A rotary valve 22 and a diaphragm device 23 are connected into the system by suitable piping and operate to vary the pressure at the top of the cooling chamber 15 to carry out the events of the cycle.

The above devices and their operations will be described more in detail hereinafter.

The cabinet 11 comprises insulated end walls 24, insulated back wall 28 (facing the front of the bar), insulated top wall 25 and a removable insulated front panel 26. The front panel may be removed by wing nuts as indicated or in any other desired manner. The bottom wall of the cabinet 11 may also be insulated and have incorporated therein a drip pan 27 for catching condensed moisture and suitably draining it by any desired means (not shown).

Thus, both the keg 12 being dispensed and storage keg 13 are held within an insulated compartment where they may be cooled below room temperature. Refrigeration, according to the invention, is applied directly to the beverage in the dispensing keg 12 and a part, or all, of this beverage is thereby cooled to dispensing temperature, in the case of beer, to around 40° F. As the storage temperature for the beverage does not have to be so low, in the case of beer, around 50° F., the same refrigerating system used for cooling the beverage in dispensing keg 12 is used to cool storage keg 13 to proper temperature by keeping the temperature of the air within the cabinet 11 at a sufficiently low temperature. The refrigeration available for cooling the air within the cabinet 11 is obtained, in part, directly from the cooling chamber 15 and, in part, indirectly from the cooled beverage in keg 12.

Referring now to Fig. 2, the cooling chamber 15 and associated apparatus is suspended by one or more structural members, indicated by 31, these members being secured to the top wall 25 of the cabinet 11. It will be understood that the insulating walls of the cabinet will be suitably reenforced or braced for mechanical strength without interfering with their heat insulating properties.

The cooling chamber 15 comprises a lower chamber body 32 made of aluminum or similar good heat conducting material. The body 32 will have smooth inside walls to make it easy to keep clean. The body 32 has welded thereto, or otherwise secured thereto in good heat conducting relation, a cooling coil 33. This cooling coil will be connected to the refrigerating apparatus 19 in a manner hereinafter described more in detail. The cooling chamber 15 has a removable top 34 secured to the body 32 by a series of thumb nuts 35. A gasket 36 is interposed between the cover 34 and body 32 to maintain a gas-tight connection for the beer under pressure within the cooling chamber 15. A removable cover 40 for cabinet 11 permits access to the thumb nuts 35 after removal of the tap rod 16. Thus, the cover 34 may be easily removed for cleaning and inspection of the cooling chamber 15.

Connected to an upper edge of the body 32 is a seat 37 for a stone filter 38. A fitting 39 has a screw threaded connection with the seat 37 for holding the stone filter 38 in place and also for

providing a connection to the air pressure lines for carrying on the method of the invention as will appear hereinafter. The filter 38 may be of any material which will prevent froth from the beer passing out of the cooling chamber 15 and yet will permit free passage of gas. A disk of carborundum, alundum or of any other porous stone may be used.

For tapping a beer keg a tap hole is usually provided in the top wall of the keg 12, off center. This tap hole has threaded therein a metal plug 43 and it is the custom, when a keg is shipped full of beer from the brewery, for a cork (not shown) to be inserted within the hole in collar 43. This cork is pushed out of the hole in collar 43 into the keg by the insertion of the tap rod, as will be understood by those skilled in the art.

Secured to the metal plug 43 is a tap bush indicated in general by 41. Tap bush 41 comprises a tap bush casing 42 having a bayonet slot engagement 44 with the metal plug 43 to hold flange 45 tightly against the top surface of plug 43.

Within the tap bush casing 42 is a shank or sleeve 46 having projections 47 vertically slidable in slots in the casing 42. A wing nut 50 has a flange engaging in an annular groove 51 in shank 46 and has a threaded connection 52 with casing 42. Thus by screwing down the wing nut 50, washer 53 may be compressed between an annular seat on the lower end of shank 46 and the metal plug 43 to maintain a gas-tight connection at this point.

To maintain the keg gas-tight, it is desirable to have a tight sliding connection between tap rod 16 and shank 46. For this reason, the upper end of shank 46 is provided with a stuffing box 54 in which is located a packing 55. A thumb nut and gland, indicated by 56, is threaded to stuffing box 54 for the purpose of exerting pressure on packing 55 to maintain a gas-tight seal with tap rod 16 at this point.

The shank 46 is provided with a branch 59 communicating with annular space 57 leading to the interior of keg 12. A fitting 60 is threaded into branch 59 and carries a seat for the stone filter 62, which may be similar to stone filter 38. Filter 62 is held in place by a fitting 61 to which is threaded a two-way cock 63. Cock 63 comprises a plug 64 and branches 65 and 66 adapted to be connected to piping as will hereinafter appear. Two-way cock 63 may be operated from the position of the handle indicated in Fig. 2 to the position indicated in Fig. 2a. The position in Fig. 2 is the position for regular cyclic operation of the system. The position in Fig. 2a is used during tapping of the keg.

The tap rod 16 comprises an outer tube 69 and an inner tube 70. The outer tube 69 is mainly for withdrawing and returning the beer from and to the keg for cooling. Inner tube 70 is for dispensing the brew.

Concentric tubes 69 and 70 are connected by a bottom fitting 71 adapted to rest on or near the bottom wall of keg 12. Fitting 71 has holes 74 in close proximity to the bottom of the keg so as to be able to dispense substantially the entire contents of the keg. Outer tube 69 has holes 73 for withdrawing the beer to be cooled.

Between the ends of the tap rod is a collar 75 located just above a series of holes 76 in the outer tube 69. Holes 76 are adapted to line up with holes in sleeve 88 for the purpose of communicating with the cooling chamber 15.

Connecting inner and outer tubes 69, 70 at the

top is a top fitting 72 connected with the faucet 14. Below the top of the tap rod 16 is a sealing assembly 71 comprising a stuffing box 78 holding packing 79 and screw threaded gland structure 80. By rotating the members 78 and 80 relatively, the pressure between packing 79 and tap rod 16 may be varied. The assembly just described is for the purpose of covering holes 76 in the tap rod during the tapping operation in a manner described below.

To form a tight engagement between the tap rod 16 and cooling chamber 15, a packing assembly is provided comprising sleeve 88, packing collars 86 and 87, packing box 85, gland 89 and a nut member 83 having screw threaded engagement 84 with the top 34 of the cooling chamber 15. From an examination of this construction, it will be apparent that by rotating the hand nut 83, packing collars 86 and 87 may be clamped tightly in place, forming tight joints above and below the holes 76 between the walls of the cover 34 and the body 32 on the one hand and the outer tube 69 on the other hand. It will be understood that by loosening the hand nut 83, the tap rod 16 may be slid lengthwise through the cooling chamber 15.

Referring now to Fig. 3, the diaphragm device 23 comprises a set of shells 90 and 91 clamping between them a flexible diaphragm 92. Pipe 116 is connected to one side of diaphragm 92 and pipe 117 is connected to the other side. The device 23 operates with a pressure difference on opposite sides of the diaphragm, but the high pressure side alternates. First, the pressure of one side of the diaphragm 92 is higher and then the pressure on the other side is higher, as the cycle proceeds. The diaphragm 92 alternately takes a position substantially against one shell and then against the other shell. In changing from one extreme position to the other, the diaphragm 92 displaces a certain volume, which volume may be substantially equal to the volume of the cooling chamber 15 which, in some cases, may be about a quart.

For controlling the pressure on opposite sides of diaphragm 92, a rotary valve arrangement 22 is provided comprising a casing 95 having a series of ports 96, 97, 98, 105 and 106. Within the casing is a rotor 99 having an arcuate port 100 adapted to register alternately with ports 105 and 97. The rotor 99 has an annular groove 101 continually registering with port 96, this groove being connected to port 100 by groove 102. Rotor 99 also has an equalizer port 103 connecting, at times, ports 106 and 98.

The rotor 99 is driven at a suitably slow speed, depending upon the characteristics it is desired to give to the cycle, for example, one revolution per minute. The rotor is driven by a suitable source indicated by 104 which may be a small electric motor having a speed reduction unit incorporated therewith. The atmosphere port 105 is connected to a variable stop cock 107 so as to control the rate at which air is permitted to discharge. By varying cock 107, the speed at which the beer is withdrawn from the keg can be controlled.

The apparatus is connected by suitable piping as follows (Fig. 1):

The compressed air tank 21 has a suitable control valve 110 and pressure gauge 109. A pipe 111 connects valve 110 with a T-fitting 113. Pipe 111 has a check valve 112 incorporated therewith to permit air to pass from storage tank 21 to the system so long as pressure in the system is less

than in the tank 21. When pressure in the system exceeds pressure in the tank 21, as for example, when a new keg of comparatively warm beer is tapped, check valve 112 prevents the keg pressure from backing up into air tank 21 and from communicating with any other air lines in case other systems according to the invention are operated from the same air tank 21.

T-fitting 113 communicates with ports 97 and 98 (Fig. 3). T-fitting 113 is also connected to pipe 114 which is connected to flexible tubing 115, which in turn is connected to branch 65 of two-way valve 63. It will be understood that the piping herein will be generally either of copper or of rubber. For ordinary piping which may remain in fixed position, copper will be generally used and for piping which has to be moved or bent frequently, rubber or flexible composition will be used.

Referring now also to Fig. 3, pipe 116 connects port 96 with shell 91. Pipe 117 is connected to shell 90 of device 23 and extends to T-fitting 123 which is connected by pipe 119 to valve 120. Valve 125 is connected in pipe 117 to control the rate of returning beverage to the keg from cooling chamber 15. Valve 120 is connected to fitting 124. Fitting 124 is connected through flexible tubing 121 to branch 66 of two-way valve 63. Fitting 124 is also connected by pipe 122 to fitting 39 on the cooling chamber 15. Pipe 118 connects T-fitting 123 with port 106.

The refrigerating apparatus is of generally conventional construction. It comprises the usual compressor 131 driven by a suitable motor 132, delivering its compressed gas to a condenser 130, thence through pipe 126 to expansion valve 127 on cooling coil 33. The expansion of the refrigerant absorbs heat from the beer within the cooling chamber 15. The warmed expanded gas returns through suction pipe 128 to the compressor 131. The compressor 131 may have a suitable pressure control 129 controlled by the pressure in suction pipe 128 for controlling the electric motor 132.

The expansion valve 127 may be of a conventional construction having a feeler bulb 133 connected to the discharge end of coil 33. The feeler bulb modifies the pressure regulating action of the expansion valve 127 to keep the coil 33 completely refrigerated when the beer is at dispensing temperature.

The temperature of the beer is controlled as follows: As comparatively warm beer enters the cooling chamber 15, it warms the refrigerant within the expansion coil 33, causing the corresponding saturation pressure of the refrigerant to rise above the setting of refrigerator pressure control 129. This starts electric motor 132 operating which causes pump 131 to supply liquid refrigerant under pressure to expansion valve 127. The evaporation of the refrigerant passing through expansion valve 127 applies refrigeration to expansion coil 33, cooling the beer. As soon as the temperature of the beer drops to a predetermined value, the corresponding decrease in saturation pressure of the refrigerant within the expansion coil operates pressure control 129 to stop the motor 132.

Referring now to Figs. 5 and 6, the cooling chamber here illustrated comprises a body 134 having a cooling coil 135 cast therein. Body 134 may be made of cast aluminum or any other desired metal which can be cast around a cooling coil. The body 134 has a removable top 136 screw threaded to the body 134 at 143. A gasket 142

seats in body 134 and has sealing engagement with the margin of top 136 when it is screwed down into place. Top 136 may be suitably webbed for strength, the webs being indicated by 141.

The cooling chamber is provided with an inner space 137 and an outer space 139 connected by a spiral chamber 138. The convolutions of the spiral chamber 138 are separated by a spiral rib 140 having a machine fit with the comparatively flat surface of body 134.

This cooling chamber is mounted upon the tap rod 16 and has sealing engagement therewith in a manner similar to that described in connection with Fig. 2. To provide sealing engagement, sealing washers 146 and 147 are provided, separated by a longitudinally movable sleeve 148 having a series of holes 149 communicating with inner space 137. Lower washer 147 seats in the body 134 and upper washer 146 seats in the top 136. A gland 150 operated by hand nut 151 threaded onto tubular extension 154 clamps the washers 146 and 147 tightly against the inserted tap rod.

The cooling chamber may be supported in any desired way as by the flange 152 from the top wall of the keg cabinet 11. A connection 153 is provided at the top of outer space 139 for connection to a pipe similar to connection 37 in Fig. 2. It will be understood that the cooling chamber above described will be used in a way similar to the cooling chamber shown in Fig. 2.

As the beverage is being withdrawn from the keg, it enters inner space 137, passes through the spiral path 138 to outer space 139; when the beverage is returned to the keg, its movement is reversed. The spiral path 138 has the advantage of increasing the surface to volume ratio, providing increased surface contact between the beverage and the refrigerated surface of the cooling chamber; the spiral path being of restricted cross section, increases the velocity of flow, thus obtaining better heat transfer.

Operation

Referring now to Figs. 1-4, the operation of the entire system will now be described. First, the operation of the system will be considered after a new keg has been connected in for some time and the operation has reached a stabilized operating cycle. In the drawings, the parts are shown with the beer just beginning to be returned back into the keg 12 from the cooling chamber 15. The port 100 (Fig. 4a) in rotor 99, rotating in the direction of the arrow X, has just begun to communicate with port 97 and air from air tank 21 passes through pipe 111, check valve 112, fitting 113, port 97, port 100, grooves 102 and 101, port 96, pipe 116, putting full air pressure on the right side of diaphragm 92 in Fig. 3.

The pressure on the left side of diaphragm 92 in Fig. 3 will be less than the pressure on the right side as the hydraulic head of the beer above the level of the beer in keg 12 reduces the pressure on the left side. The diaphragm 92 will, therefore, slowly move to the left. This movement will force the air with which the entire meter 23 has just been filled through pipe 117, valve 125, fitting 123, pipe 119, valve 120, fitting 124, pipe 122 into the top of cooling chamber 15. Since keg 12 is continuously under full air pressure (pipes 114, 115, valve 63 and annular space 57) the air pressure on the top of the surface of the beer in cooling chamber 15 and in the top of the keg must be equal. Hence, the beer is free to return from cooling chamber 15 through

openings 16 and through the annular space between tubes 69 and 70 and through openings 73 to the keg by gravity. The rotation of rotary valve 22 is sufficiently slow to give ample time to empty the cooling chamber 15.

To make sure that cooling chamber 15 is completely empty, after communication between ports 100 and 97 is discontinued, equalizer port 103 connects ports 106 and 98 (Fig. 4b) whereby air pressure is directly connected through pipe 118 to pipe 119 thus, in effect, short circuiting or shunting diaphragm device 23. The application of full air pressure above the surface of the beer in cooling chamber 15 equal to the air pressure on the surface of the beer in the keg insures complete evacuation of the beer from the cooling chamber.

Shortly after communication is discontinued between ports 100 and 97, port 100 communicates with atmosphere port 105. This permits the air pressure within the keg to return a measured portion of beer to the cooling chamber 15. The air in the cooling chamber 15 exhausts through pipes 122 and 119 and pushes diaphragm 92 from the left hand position in Fig. 3 to the right. The air on the right side of diaphragm 92 exhausts through pipe 116, port 96, grooves 101, 102, ports 106 and 105 through variable cock 107. By adjusting cock 107, the rate at which beer is withdrawn from the keg can be controlled, thus minimizing agitation of the beer and preventing foaming. Should any foaming occur, however, the stone filter 38 at the top of the cooling chamber 15 will prevent flow of the liquid bubbles while permitting the air to escape.

As soon as the diaphragm 92 is forced to its farthest right hand position, no more beer can flow into the cooling chamber 15. Thus, the capacity of the device 23 will correspond to the capacity of the cooling chamber 15 and limit the amount of beer which can flow into cooling chamber 15. For example, a displacement of one quart by the movement of diaphragm 92 will result in the displacement of approximately one quart of beer from the keg to the cooling chamber 15.

The valve rotor 99 has now rotated so that ports 100 and 97 are about to register, this being the position shown in the drawings and at which the description of the cycle was started. All the while the cooling chamber 15 is filling up with beer and emptying its contents, the beer is being subjected to the cooling action of the refrigerator coils 33.

The operation of the system just after a warm keg is connected will be similar to that above described but with a slight difference. The pressure of the gas above the beer in a newly connected keg may be considerably higher than the pressure in the storage tank. The operation above described will be the same under these circumstances, except that pressure for running the system will be supplied from the keg through pipe 114, check valve 112 thereby preventing this excess pressure from being communicated to the storage tank 21 or to any other similar systems which may be in operation off the same air compressing apparatus. As soon as the excess pressure within the beer is relieved, check valve 112 opens and air pressure from the storage tank 21 operates the system.

Provision is made to prevent loss of beverage while tapping a new keg. To install a new keg, first move valve 63 to the position shown in Fig. 2a and shut valve 129. This connects the top of the

cooling chamber 15 with the top of the keg, insuring the return of any beer in the cooling chamber to the keg. Then loosen gland nuts 83 and 56. Tap rod 16 may then be removed simply by lifting straight up and pulling it out of the keg. Wing nut 50 is then unloosened and the tap bush 41 is also removed from the keg 12. Air pressure cannot escape through the tap bush 41 because of the position of valves 63 and 120. The empty keg 12 is then removed from the cabinet 11 and storage keg 13 is lined up in the position of keg 12. A new storage keg is placed in the position of old storage keg 13.

The tap bush 41 is placed in the tap plug 43 of the new keg 12 and the tap rod is inserted through the center of cooling chamber 15 after first placing the packing 79 over holes 76. Tap rod 16 is pushed down through packing 55 to push the cork out of ring 43. As soon as the tap rod touches the beer, pressure forces the beer up the tap rod between tubes 69 and 70, but it cannot escape because packing 79 is over holes 76. Keg pressure cannot escape since valve 63 communicates with cooling chamber 15 which is sealed by the position of the tap rod. As the tap rod is pushed down into the keg, packing 79 and its assembly slides upward and the tap rod is pushed home quickly until it hits the bottom of the keg at which time the holes 76 line up with the openings in sleeve 88. The hand nuts 83 and 56 are then tightened, valve 63 turned to the position shown in Fig. 2, valve 120 is opened and the system is ready for operation. Since the keg 12 and cooling chamber 15 are in communication through the two-way valve 63 during tapping, the cycle always starts with cooling chamber 15 empty.

A certain amount of time should be allowed for the cooling system to operate on a new keg of beer before dispensing. However, due to the fact that the dispensed brew is drawn from the bottom of the keg and since the cooling action is applied directly to the beer in the bottom of the keg, the beer may be dispensed after the system has been in operation but for a very few minutes.

The invention has been illustrated as applied to a single unit using a single cabinet holding a single dispensing keg and a single storage keg. A typical job may be said to comprise two units of the type above described, thus comprising two cabinets, four kegs, two cooling chambers, two tap rods, two dispensing faucets, two rotary valves and two diaphragm meters. If desired, however, one refrigerating machine and one compressor and storage tank may be used with a two unit installation. In fact, one refrigerating machine and one compressor and storage tank may be used with as many keg units as the machines have capacity. Also, instead of using two separate rotary valves for a two unit installation, both rotary valves may be incorporated in a single rotor and a single stator having two complete sets of ports instead of one set.

The best dispensing temperature for the ordinary brewed beverages, such as beer, ale, etc. now on the market, is considered to be around 40° F. Consequently, the system must keep the stratum of beer at the bottom of the keg at about this temperature. The equilibrium pressure of ordinary brews at this temperature is about 12 to 14 lbs. per square inch. Consequently, the pressure in the air storage tank is kept at the same pressure so as to keep the dissolved gases in the brew and thereby maintain its palatability.

According to best practice, the beer while being stored in readiness for dispensing should be maintained at a temperature of 50° F. or less. The equilibrium pressure of ordinary brews at this temperature is about 20 to 25 lbs. In practice, however, a keg to be tapped may have a temperature somewhat higher than 50° F. with a correspondingly higher equilibrium pressure. After the beer is cooled down to 40° F., the pressure above the beer in the keg may not be reduced to corresponding equilibrium pressure, since upon cooling down the carbon dioxide is not reabsorbed with the beverage in quiescent state.

It is for these reasons the check valve 112 is necessary. This valve prevents backing up of the higher keg pressure into the air tank and insures the utilization of the excess pressure to operate the system since it is desired to maintain the gas in the keg being dispensed at the equilibrium pressure to prevent foaming when the beverage is dispensed.

Since it is desired to keep the beer in the bottom of the keg being dispensed at around 40° F., the cooling chamber should cool the beer to a somewhat lower temperature, say, around 35° F. Care should be taken not to freeze the beer as this destroys its palatability and appearance.

Thus a system has been described which is superior to beer cooling systems presently in use. No special barrel construction is necessary. Ordinary barrels may be used. The beer may be quickly cooled and dispensed shortly after the new keg is connected. The present system is easy to clean. All parts in which the beer travels are easily accessible for cleaning purposes. The parts are of simple construction. There is nothing to get out of order. It is easy to install a new keg.

Stratified cooling is obtained. It is possible to control the degree of stratification by the speed at which the beer is permitted to return to the keg from the cooling chamber, this in turn being controlled by the adjustable valve 125. The dispensing is direct. There is no foaming since the lift is small and the keg normally operates at the equilibrium pressure of the beer. The shortness of the path between keg and dispensing faucet and the concentric construction of the tap rod insures practically the same temperature of the beverage at the dispensing faucet as in the bottom of the keg.

The installation of a standby keg in the same insulated cabinet with the dispensing keg keeps the standby keg at storage temperature without requiring special storage rooms or the application of special cooling apparatus to the standby kegs.

The holes 73 communicating with the transfer tube 69 are located a predetermined distance above the hole 74 so as to insure leaving a predetermined amount of beverage in the bottom of the keg which cannot be withdrawn by the cooling system. The holes 74 at the bottom of the tap rod are located substantially at the bottom of the keg. This arrangement insures dispensing the beer in the very bottom of the container, preventing this beer from being withdrawn by the cooling system when it is desired to dispense it.

While certain novel features of the invention have been disclosed and are pointed out in the annexed claims, it will be understood that various omissions, substitutions and changes may

be made by those skilled in the art without departing from the spirit of the invention.

What is claimed is:

1. The method of cooling a beverage which comprises maintaining a gas pressure on the beverage in a container, applying a reduced pressure to a cooling chamber above the container to transfer the beverage to said chamber, applying a cooling medium to said cooling chamber and then applying a pressure to said chamber at least as high as the pressure in said container to return the beverage to said container.

2. In a beverage cooling system, a transportation container, a cooling device above said container, means for applying gas pressure to said container, means for alternately applying gas pressure and a reduced pressure to said cooling device, whereby said beverage is alternately withdrawn from said container to said cooling device and returned by gravity from said cooling device to said container.

3. In an arrangement for cooling and dispensing beer and like beverage, a keg or other container for the liquid, a tap rod comprising an outer tube passing through the walls of the container and an inner tube within said outer tube forming an annular space therebetween, said tap rod extending into the beverage, a dispensing valve at the upper end of said inner tube, a cooling arrangement external of said container, and means for transferring beverage from said annular space to said cooling arrangement.

4. In a beverage cooling system, a cooling chamber having top and bottom walls with beverage space therebetween, a tube passing through said top and bottom walls and having a passage adapted to communicate with the interior of said chamber, said bottom wall having a stuffing box, a packing ring in said stuffing box surrounding said tube, a sleeve above said packing ring, a second packing ring above said sleeve, a gland member threaded onto said upper wall for squeezing both said packing rings, said upper packing ring providing a seal between said upper wall and said tube, said lower packing ring providing a seal between said lower wall and said tube, whereby upon loosening said gland member said tube may be easily slid upwardly through said chamber.

5. In a fluid transfer system, a chamber having spaced walls with fluid space therebetween, a tube passing through said spaced walls and having a passage adapted to communicate with the interior of said chamber, one of said walls having a stuffing box, a packing ring in said stuffing box surrounding said tube, a sleeve adjacent said packing ring, a second packing ring adjacent said sleeve, a gland member secured to said other wall for squeezing both said packing rings, said packing rings providing seals between said walls and said tube, whereby upon loosening said gland member said tube may be easily slid with respect to said chamber.

6. In a heat transfer device, a chamber having a bottom wall and an annular side wall, a cooling device associated with said chamber, a top wall and an inner annular side wall forming with said first side wall an annular space, said chamber having a central space, a tortuous conduit between the central space and annular space, said central space and said annular space having conduits communicating therewith.

7. In a heat transfer device, a chamber comprising a body member having a bottom wall and an annular side wall, a cooling coil embedded in said bottom wall, the upper surface of said bot-

tom wall being substantially flat but rising slightly from the center to the periphery, a cover member having a top wall and having an annular side wall forming with the side wall of the body an annular space, said cover member having a central recess and a spiral wall connecting said central recess and said annular space and forming a spiral conduit between the central space and annular space, a tube passing through said bottom wall and said top wall, said bottom wall having a stuffing box, a packing ring in said stuffing box, a sleeve above said packing ring, a second packing ring above said sleeve, and a second member adjustably secured to said cover whereby to seal the passage of said tube through said top and bottom walls, said annular space having a conduit communicating therewith.

8. The method of cooling and dispensing brew which comprises installing a plurality of brew containers in an insulated cabinet, dispensing brew from one of said containers, applying refrigeration from a cooling system to that container from which brew is dispensed and cooling the brew in another container by heat flow through its walls into the air in the cabinet and thence into the same cooling system.

9. In a system for controlling the temperature of a beverage, such as beer, a container for the beverage, a dispensing arrangement for dispensing beverage directly from the container, a cooling device, means for transferring beverage from the container to said cooling device and back to said container, a refrigeration circuit in heat exchange relation with said cooling device having a compressor and a motor drive therefor, said refrigeration circuit having a pressure control on the suction side of said compressor, said control operating to start said compressor motor when said suction pressure is above a predetermined amount corresponding to comparatively warm beverage in said cooling device and to stop said motor when said suction pressure falls below a predetermined amount corresponding to comparatively cold beverage in said cooling device.

10. In a beverage cooling system, a transportation container, means for applying a higher than atmospheric pressure to said container, a cooling device outside of said container, a power driven device for constantly, alternately applying on said cooling device a pressure less than the pressure in said container and a pressure at least as high as the pressure in said container, whereby said beverage is alternately transferred from said container to said cooling device and returned from said cooling device to said container, and a dispensing device for dispensing beverage direct from said container.

11. In a beverage cooling system, a container for the beverage, a fitting secured to a top wall of said container and communicating with the inside of said container, a tube passing through said top wall into the container, a cooling chamber above said container and having an opening above highest beverage level, means connecting said tube to said cooling chamber, a conduit connecting said fitting and said opening, a source of pressure connected to said fitting, a pipe line connected to said opening for alternately applying to said cooling chamber pressure at least as high as the pressure in said container and pressure less than the pressure in said container, means for controlling fluid flow through said line, means for controlling fluid flow between said

source and said fitting, and means for controlling fluid flow through said conduit.

12. In a beverage cooling system, a container for the beverage, a fitting secured to a top wall of said container, a tube passing through said fitting into the container, a cooling chamber above said container having an opening above the highest beverage level, means connecting said tube to said cooling chamber, said fitting having a two-way valve communicating with the inside of said container, said valve having two branches, a conduit connecting one of said branches and said opening, a source of pressure connected to the other branch, a pipe line connected to said conduit for alternately applying to said cooling chamber pressure at least as high as the pressure in said container and pressure less than the pressure in said container, and a valve between said line and said conduit.

13. The method of cooling a beverage, such as beer, which comprises constantly repeatedly transferring the beverage from its container to a cooling device and returning the cooled beverage to said container, controlling the amount of refrigeration applied to said cooling device by the temperature of the flowing beverage, and independently dispensing said beverage direct from said container.

14. In a cooling system for beverages, such as beer and the like, a container for the beverage, a tap rod extending through a wall of said container to the bottom thereof, said tap rod comprising an inner tube and an outer tube, a cooling chamber above said container associated with said outer tube, a refrigerating system including a cooling passage connected to the wall of said cooling chamber, said inner tube passing through said chamber, a dispensing faucet on the outer end of said inner tube, a source of gas under pressure connected to said container for maintaining pressure on the beverage, a valve arrangement connected to said source, a diaphragm device between and connected to said valve arrangement and said cooling chamber, said valve arrangement periodically communicating to said diaphragm device pressure less than the pressure of said source and pressure at least as great as the pressure of said source, whereby the beverage flows from said container into said cooling chamber and returns periodically, thus cooling the beverage in the container.

15. In a cooling system for beverages, such as beer and the like, a container for the beverage, a tap rod extending through a wall of said container to the bottom thereof, a cooling chamber above said container, a refrigerating system for cooling said chamber, a conduit connecting said container and said chamber, a dispensing valve on the end of said tap rod, a source of gas under pressure connected to said container for maintaining pressure on the beverage, a valve arrangement connected to said source, a volume limiting device between and connected to said valve arrangement and said cooling chamber, said valve arrangement periodically communicating to

5 cating to said volume limiting device pressure less than the pressure of said source and pressure at least as great as the pressure of said source, whereby the beverage flows from said container into said cooling chamber and returns periodically.

10 16. In a beverage cooling system, a beverage container from which beverage is dispensed, a cooling chamber located above the level of the beverage in said container, means for transferring beverage between said beverage container and said cooling chamber, a compressed gas tank, a check valve connected to said tank, a line connecting said check valve and the top of said container to maintain pressure on the beverage in said container, a diaphragm device connected to the upper part of said cooling chamber, a rotary valve between said check valve and said diaphragm device, said rotary valve having a pressure port connected to said check valve, an atmosphere port, a diaphragm device port connected to said diaphragm device and a by-pass port connected to said chamber, whereby the rotor of said control valve connects said diaphragm device port alternately to said pressure port and said atmosphere port, and whereby said rotary valve connects said pressure port and said by-pass port after said pressure port is disconnected from the diaphragm device port.

15 17. In a beverage cooling system, a beverage container from which beverage is dispensed, a cooling chamber located above the level of the beverage in said container, means for transferring beverage between said container and chamber, a compressed gas tank, a check valve connected to said tank, a line connecting said check valve and the top of said container to maintain pressure on the beverage in said container, a volume limiting device connected to the upper part of said cooling chamber, a control valve between said check valve and said volume limiting device, said control valve having a pressure port connected to said check valve, an atmosphere port, a volume limiting device port connected to said volume limiting device, whereby said control valve connects said volume limiting device port alternately to said pressure port and said atmosphere port.

20 18. In a beverage cooling system, a transportation container, means for applying a higher than atmospheric pressure to said container, a cooling chamber outside of said container, said cooling chamber being of very small capacity as compared to that of said container, refrigerating devices in heat transfer relation to said chamber, a power driven device for constantly, alternately applying on said cooling chamber a pressure less than the pressure in said container and a pressure at least as high as the pressure in said container, whereby small amounts of said beverage are alternately transferred from said container to said cooling chamber and returned from said cooling chamber to said container.
